Primary Examiner — Steven J Czyz(74) Attorney, Agent, or Firm — Ying-Ting Chen(57) CLAIM

The ornamental design for a pill container as shown and described.

DESCRIPTION

FIG. 1 is a perspective view of a pill container showing my new design, illustrating the ornamental design of the interior compartment of the container body with the cover thereof in open state;

FIG. 2 is another perspective view thereof;

FIG. 3 is a top view thereof;

FIG. 4 is a front view thereof;

FIG. 5 is a bottom view thereof;

FIG. 6 is a rear view thereof;

FIG. 7 is a left side view thereof; and,

FIG. 8 is a right side view thereof.
